UNITED STATES PATENT OFFICE.

HIRAM H. SPONENBURG, OF GURNEE, ILLINOIS, ASSIGNOR, BY MESNE ASSIGNMENTS,
TO OTTO R. BARNETT, OF CHICAGO, ILLINOIS.

RAIL-ANCHOR.

1,350,676.

Specification of Letters Patent. Patented Aug. 24, 1920.

Application filed October 3, 1919. Serial No. 328,252.

To all whom it may concern:

Be it known that I, HIRAM H. SPONENBURG, a citizen of the United States, residing at Gurnee, in the county of Cook and State 5 of Illinois, have invented certain new and useful Improvements in Rail-Anchors, of which the following is a specification.

My invention relates to a device for resisting the tendency of railroad rails to 10 move longitudinally, such devices being known generally as rail anchors, anti-creepers and rail stays.

The primary object of the invention is to provide a novel one-piece device of the 15 above character which may be readily applied to rails, the base flanges of which vary in width or thickness, which will maintain its initial grip on the rail with spring pressure and which will increase its grip on the 20 rail during any longitudinal movement of the rail.

The more specific objects of the invention are to provide a rail anchor made entirely of spring metal having jaws adapted 25 to engage opposite edges of the base flange of the rail and which are so formed that they will minimize the rocking action of the anchor during the presence of a creeping pressure on the rail. The preferred 30 form of anchor also contemplates the portion of the anchor intermediate the jaws being formed so that it will flex to facilitate the application of the device to its operative position on the rail and which will also flex 35 in a manner to increase the grip of the jaws on the rail base during the presence of a creeping pressure.

A further object of the invention is to provide a novel spring metal anchor device 40 which is formed so that it will flex to increase the grip of its jaws on the rail base when the rail moves longitudinally in either a forward or rearward direction.

The invention has for further objects such 45 other novel and improved construction as will be hereinafter described and claimed for carrying out the above mentioned objects and such other incidental objects as will appear from the following specification.

The invention is illustrated in a preferred embodiment in the accompanying drawings wherein:

Figure 1 is a plan view of a rail anchor 55 device constructed in accordance with my

invention and illustrating the manner in which the device is flexed during the application of the jaws to the edge of the rail base;

Fig. 2 is a view in perspective illustrating 60 the device shown in Fig. 1 in its applied position to the base flange of the rail;

Fig. 3 is a front view in elevation of the anchor shown in the preceding figures, and illustrating one of the positions which it assumes during its application to the rail; 65

Fig. 4 is a view in perspective of my preferred form of rail anchor;

Fig. 5 is a plan view of a modified form 70 of rail anchor showing the same applied to the base flange of a rail. The rail in this figure being shown in dotted line; and

Fig. 6 is a sectional view taken on line 6—6 of Fig. 5.

Like characters of reference designate 75 like parts in the several figures of the drawings.

Referring first to Figs. 1 to 4 inclusive of the drawings, 10 designates a railroad rail and 11 one of the cross ties on which the 80 rail is supported. The device shown in the above figures is made from a piece of relatively thin spring metal so that it may be readily flexed when it is applied to the rail or during a creeping pressure to increase its 85 grip on the rail, as will be hereinafter more specifically described. The device is provided with jaw portions 12, 13 which are formed by bending the metal blank in, preferably but not necessarily, opposite directions. The portion 14 of the anchor intervening between the jaw portions is narrower than the jaw portion so as to extend 90 under the base flange of the rail and to provide vertical edges which are formed with recesses 15—15, 16—16 which fit over opposite edges of the base so that the lips 17, 18 of the jaws will bear against the inclined surfaces of the rail base. The portion of the anchor intervening between the jaws 12, 13 95 is curved, preferably outwardly from the tie, so that the distance between the jaws is normally less than the width of the rail base to which the device is applied, thus requiring the curved portion 14 to be tensioned that is, partly straightened out when the anchor is applied to the base flange of the rail. The portion of the metal blank adjacent the jaw 13 is bent as indicated at 100 19 to provide a tie-abutting flange 20 and 105

110

the free end 21 of the blank extends from the tie abutting flange to the inner face of the curved portion 14.

- To apply the device to the rail the jaw 13 is engaged with one edge of the base flange as shown in Fig. 3, so that the lips 18, 18 bear against the upper surface of the flange. The lips are preferably bent at an angle to each other and stand diagonally across the base of the flange, so that they will yield as they are forced upward on the inclined surface of the rail base. A crow-bar 22, or other suitable device, is positioned in the bend of the jaw 12 (Fig. 3) and the jaw forced outwardly until the curved portion 14 of the anchor is straightened out sufficiently to permit the edge of the lips 17, 17, to clear the opposite edge of the rail base substantially as illustrated in dotted lines in Fig. 1. As the jaw 12 is being forced outwardly it is also raised slightly so that it will snap over the edge of the rail base. The upper edges of the lips 17, 17, are preferably beveled so that they will bear against and ride over the edge of the rail base, and in this way facilitate the application of the device to the rail. The tendency which the curved portion 14 of the anchor has to return to the normal position from which it was sprung causes the recesses 15, 16, of the jaws 12, 13, to take a firm grip on opposite edges of the rail base. When the device is applied to a rail having a base flange of maximum thickness, the inner edges 23, 24, of the recesses 15, 16, stand out of engagement with the vertical edges of the rail base. When the device is applied to rails having base flanges of such thickness as will permit the recesses of the jaws to be forced entirely on the flange, the edges 23, 24 of the recesses engage the vertical edges of the base flange and during a creeping pressure will take a biting hold thereon. When the rail creeps in a direction toward the tie 11, the jaw portions, being gripped to the edges of the base flange by spring action, move with the rail while the curved portion is subjected to a further flexing action by being in contact with the relatively stationary arm 21 of the tie-abutting foot 20. This additional flexing of the portion 14 of the anchor, it will be seen, tends to shorten the distance between the jaws 12, 13 and increases their grip transversely of the rail base.

In Figs. 5 and 6 I have illustrated a modified form of device which consists of jaw portions 12^a, 13^a formed substantially the same as jaws 12, 13, shown in the preceding figures, and provided with a tie-abutting flange 20^a and an extension 21^a which bears against the inner face of the curved portion 14^a in substantially the same manner as that described in connection with the preceding figures, and is adapted to perform substan-

tially the same functions as previously described, that is, to grip the edges of the rail with a spring pressure and to increase said grip by subjecting the curved portion 14^a to an additional flexing action during the presence of a creeping pressure on the rail tending to move the rail longitudinally toward the tie 11^a. In this form of the anchor, instead of making the jaw 12^a with a relatively short hook portion as shown in Figs. 1 to 4 inclusive, I have provided the jaw 12^a with an extension or arm 25 which extends transversely of the rail base. The outer end of the portion 25 is bent so as to extend longitudinally of the rail and bears against the outer face of the curved portion 14^a so that an increased gripping action will be produced by causing an increased flexing action of the curved portion 14^a when the rail creeps in a direction away from the tie 11^a, particularly during the winter when the ballast is frozen, so as to prevent the rail anchor from moving with the rail.

I claim:

1. A rail anchor having jaws adapted to engage opposite edges of a rail base at a plurality of points; the distance between the jaws being normally less than the width of the rail base, and the device being adapted to be flexed to permit its application to the rail.
2. A rail anchor having jaws adapted to engage opposite edges of a rail base at a plurality of points; the distance between the jaws being normally less than the width of the rail base, and the device being adapted to be flexed laterally of the rail in its application to the base flange thereof.
3. A rail anchor formed with bends providing jaws adapted to engage opposite edges of a rail base at a plurality of points; the distance between the jaws being normally less than the width of the rail base, and the device being adapted to be flexed to permit its application to the rail.
4. A rail anchor having jaws adapted to engage opposite edges of a rail base at a plurality of points and formed with a bend intermediate the jaws adapted to be strained in its application to a rail.
5. A rail anchor having a tie abutting foot and a body portion provided with jaws having recesses in spaced relation to each other adapted to engage opposite edges of the base flange of a rail at a plurality of points and formed with a bend intermediate the jaws adapted to be strained in its application to a rail whereby the initial grip of said jaws on the rail is maintained by the tensioned condition of said body portion.
6. A rail anchor comprising a piece of spring metal bent to provide a tie abutting foot and to form jaw portions which engage opposite edges of the rail base at

points longitudinally remote from each other; the distance between the jaw portions being normally less than the width of the rail base and the portion of the anchor 5 intermediate the jaws being formed with a bend adapted to be straightened when the device is applied to a rail.

7. A rail anchor comprising a piece of spring metal bent to provide a tie abutting 10 foot and to form jaw portions which engage opposite edges of the rail base at points longitudinally remote from each other; the distance between the jaw portions being normally less than the width of the rail base 15 and the portion of the anchor intermediate the jaws being formed with a bend which is flexed to permit the application of the device to the rail and which is adapted to flex during the presence of a creeping pressure 20 sure to increase its grip on the rail.

8. A rail anchor comprising a body portion formed with jaws which engage opposite edges of a rail base and formed with a tie abutment which engages with the said 25 body portion to produce a flexing action of said body to increase the grip of the jaws on the rail base when the rail moves longitudinally toward the tie.

9. A rail anchor comprising a body portion 30 formed with jaws which engage opposite edges of a rail base and formed with a tie abutment which engages with the said body portion intermediate the jaws to produce a flexing action of said body to increase 35 the grip of the jaws on the rail base when the rail moves longitudinally toward the tie.

10. A rail anchor made from a flat piece 40 of steel which is bent and the bent portion formed with recesses providing jaws which fit over opposite edges of a rail base at a plurality of points, the said jaws being adapted to be forced apart in applying the device to a rail.

11. A rail anchor made from a piece of 45 spring metal recessed to provide a plurality of spaced jaws on opposite sides of the rail and formed with a tie abutment adapted to flex the anchor to increase its hold on the rail during a creeping pressure.

50 12. A rail anchor made from a piece of spring metal recessed to provide a plurality

of spaced jaws at opposite ends of the device which engage with the base flange of the rail and formed with a tie abutment adapted to flex the anchor to increase its hold on the rail during a creeping pressure. 55

13. A rail anchor made from a piece of spring metal recessed to provide a plurality of spaced jaws at opposite ends of the device which engage with the base flange of 60 the rail and formed with a tie abutment adapted to flex the anchor to increase its hold on the rail during a creeping pressure; the portion of the anchor intervening between the jaws being formed with a curve 65 which is partly straightened to permit the jaws to be applied to their operative position.

14. A rail anchor made from a flat piece of spring metal having one end bent to provide a tie abutting foot and the bent portion recessed to provide a jaw which fits over one edge of the base flange of a rail and the other end of the device being formed with a reverse bend which is recessed to 70 provide a jaw adapted to engage the opposite edge of the rail base; the said tie abutting foot being provided with an extension engaging the portion of the device intervening between the jaws whereby the 75 device is flexed during the creeping action of the rail to increase its grip transversely of the rail.

15. A rail anchor made from a flat piece of spring metal having one end bent to provide a tie abutting foot and the bent portion recessed to provide a rail base engaging jaw the upper lips of which extend diagonally across the inclined surface of the base flange and are adapted to yield to compensate for variations in the thickness of said flange and the other end of the device being formed with a reverse bend which is recessed to provide a jaw adapted to engage the opposite edge of the rail base; the said 85 tie abutting foot being provided with an extension engaging the portion of the device intervening between the jaws whereby the device is flexed during the creeping action of the rail to increase its grip transversely 90 of the rail. 95
